US00D703985S

(12) **United States Design Patent**
Ogawa

(10) **Patent No.:** **US D703,985 S**
(45) **Date of Patent:** **** May 6, 2014**

(54) **KITCHEN COUNTER**

(71) Applicant: **Hirohisa Ogawa**, Zushi (JP)

(72) Inventor: **Hirohisa Ogawa**, Zushi (JP)

(**) Term: **14 Years**

(21) Appl. No.: **29/452,238**

(22) Filed: **Apr. 13, 2013**

Related U.S. Application Data

(62) Division of application No. 29/390,554, filed on Apr. 26, 2011, now Pat. No. Des. 694,052.

(57) **CLAIM**

The ornamental design for a kitchen counter, as shown and described.

DESCRIPTION

FIG. 1 is a front, top, and right side perspective view of a kitchen counter, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view thereof, taken along the line **8-8** in FIG. 2; and,

FIG. 9 is a cross-sectional view thereof, taken along the line **9-9** in FIG. 2.

The broken lines shown are included for the purpose of illustrating the environment in which the article resides and form no part of the claimed design.

1 Claim, 8 Drawing Sheets
